UNITED STATES PATENT OFFICE

MEYER POLLOCK, OF CHICAGO, ILLINOIS, ASSIGNOR TO RELIABLE BELT COMPANY, INC.,
OF CHICAGO, ILLINOIS, A CORPORATION OF ILLINOIS

BELT

Application filed May 31, 1930. Serial No. 458,257.

My invention relates to a belt and buckle therefor, and more particularly to a belt adapted to have different types of buckles secured thereto.

5 There are several types of buckles on the market which differ in the width of the portion by which they are secured to the belt. Heretofore it has been the practice to carry in stock several lines of belts which were 10 similar in all respects except for the end which receives the buckle. I have therefore provided a belt which readily accommodates or fits either type of buckle, thereby reducing the number of belts required in stock 15 to maintain a complete line.

An object of the invention is to provide a new and improved belt.

A further object is to provide a belt for receiving buckles of different widths.

20 A further object is to provide a belt of neat and finished appearance when used with different types of buckles.

Other objects and advantages will appear as the description proceeds.

25 Referring to the drawings:

Fig. 1 is a plan view of a portion of the belt showing one type of buckle secured thereto.

Fig. 2 is a similar view of the belt showing 30 a different type of buckle secured thereto,

Fig. 3 is a view of the lower side of a portion of the belt showing the end portion extending, and

Fig. 4 is a side view of the belt looking at 35 one edge thereof.

The belt comprises a body portion 6 of any suitable belt material. The sides of the belt are preferably parallel to the buckle end of the belt. An end portion 7 is integral with the body portion of the belt and is preferably narrower than the body portion. The end portion increases in width toward the body portion and at its widest part 8 is substantially the same width as the body portion. Intermediate the body and end portions of the belt is a pair of abrupt indentations 9, the purpose of which will appear as the description proceeds. Extending from the body portion into the end portion is a longitudinal slit 11 for receiving a retaining pin 50

12 of a buckle 13. Secured to the lower side of the belt by means of snap fasteners 15 is a strap 14 and cooperating parts 16 of the snap fasteners are secured to the end portion of the belt. The strap 14 acts as a spacing member for loops 17 which receive the opposite end of the belt when the belt is worn.

55 It is customary to provide different types of belt buckles to be secured to the belt at the place of sale in order to meet the tastes of different customers. In Fig. 1 is shown a buckle 18 of a type which clamps the opposite end of the belt to frictionally adjust the length of the belt when worn. A buckle of this type has an attaching member or ring 19 which 60 is narrower than the width of the belt. In many instances the body portion of the belt is tapered in order to accommodate a buckle having a retaining member of this width. This, however, renders the belt objectionable 65 for a buckle of the type shown in Fig. 2, because a buckle of this type will be too loose on such a belt, and also have the appearance of being too large or wide for the belt. I have also found that it adds greatly to the 70 appearance of the belt to have the body of the belt of the same width all the way to the buckle. By providing the belt between the body and end portions with indentations or 75 cut-out portions 9, it will accommodate a buckle like 18 with a neat appearance and at the same time, it will tend to hold the buckle in the plane of the belt. The wide part 8 of the end portion prevents the buckle 18 from sliding out of its place. It will be seen 80 that this is a desirable feature inasmuch as a buckle of this type does not have a retaining pin like the pin 12 of buckle 13 to hold it in position.

85 In applying a buckle like 13 to the belt, retaining pin 12 passes through the slit 11. The indentations 9 in no way interfere with the proper positioning of buckle 13 and a buckle of this type attached to the belt of my invention is the same from a mechanical, as well as 90 artistic point of view, as if the indentations 9 were absent. It will be noted that the longitudinal slit 11 extending from the body portion into the end portion, permits a slight lateral contraction of the belt whereby the re- 95

taining member of buckle 18 may be more readily secured to the belt.

It will be understood that the nature and embodiment of the invention herein described and illustrated is merely illustrative, and that many modifications may be made therein without departing from the spirit and scope of the invention.

What I claim is new and desire to protect by Letters Patent of the United States is:

- 10 1. A belt adapted for the attachment of different types of buckles comprising a body portion, an end portion, said belt having a longitudinal slit extending from the body portion to the end portion, and a pair of indentations in the edges of the belt adjacent said slit.
- 20 2. A belt adapted for the attachment of different types of buckles comprising a body portion, an end portion, an interconnecting portion between the body and end portions of narrower width than the adjacent ends of said body and end portions forming in effect a pair of oppositely disposed notches, said 25 portions having a longitudinal slit between said notches permitting a contraction of said interconnecting and end portions in attaching a narrow width buckle.
- 30 3. A belt comprising a body portion, an end portion, said belt having a longitudinal slit extending from the body portion to the end portion, a pair of indentations in the edges of the belt adjacent said slit, and a buckle fitting in said indentations and held 35 between said body and end portions.

In witness whereof, I hereunto subscribe my name this 10th day of May, 1930.

MEYER POLLOCK.
